T. A. RUDDLE & N. C. AHL.
PENCIL SHARPENER.
APPLICATION FILED AUG. 9, 1917.

1,254,539.

Patented Jan. 22, 1918.

UNITED STATES PATENT OFFICE.

THOMAS ALFRED RUDDLE AND NIELS CHRISTIAN AHL, OF PHILADELPHIA, PENNSYLVANIA.

PENCIL-SHARPENER.

1,254,539.

Specification of Letters Patent. Patented Jan. 22, 1918.

Application filed August 9, 1917. Serial No. 185,270.

To all whom it may concern:

Be it known that we, THOMAS ALFRED RUDDLE and NIELS CHRISTIAN AHL, citizens of the United States, and residents of Philadelphia, in the county of Philadelphia and State of Pennsylvania, have invented a new and Improved Pencil-Sharpener, of which the following is a full, clear, and exact description.

Our invention relates more particularly to that type of pencil sharpeners in which a cutter head is revolvably mounted and provided with cutters to accommodate the pencil.

An object of our invention is to provide a pencil sharpener of the indicated type having an improved drive means including a balance wheel on the shaft carrying the cutter head and adapted to be given momentum by a drive wheel engaging the same and arranged to be actuated from the exterior of the sharpener by tangential pressure thereon by the hand of the operator against the periphery of the actuating wheel, or equivalent impetus given to said wheel by the operator.

An important object of the invention also is to provide a cutter head having knives and guide rollers so arranged thereon as to give the pencil a uniform taper. In the preferred form the invention also contemplates the adjustment of the angular relation of the cutters and the guide rollers to vary the taper of the sharpened pencil. The invention, furthermore, may embody additional guide means particularly useful in sharpening pencils to a long taper as required by artists for example.

Reference is to be had to the accompanying drawings forming a part of this specification in which similar reference characters indicate corresponding parts in all the views.

Figure 1 is a central vertical section of a pencil sharpener embodying our invention;

Fig. 2 is a fragmentary transverse vertical section taken on the line 2-2, Fig. 1;

Fig. 3 is a detail in sectional plan view on the line 3-3, Fig. 1;

Figs. 4, 5 and 6 are respectively horizontal sections on the lines 4-4, 5-5, and 6-6, Fig. 2;

Fig. 7 is a detail in sectional plan view on the line 7-7, Fig. 1, the view being made on a reduced scale;

Fig. 8 is a detail in vertical section on the line 8-8, Fig. 7;

Fig. 9 is a perspective view of one of the knives;

Fig. 10 is a partly sectional side elevation of a modified cutter head having the knives 60 and guide rollers in fixed positions.

Referring more particularly to the form of the invention shown in Figs. 1 to 7, a suitable hollow base 10 is provided having a bottom 11 and a cap 12, said parts being 65 preferably in practice produced from sheet metal. A glass dome 13 rests on the base 10 and has an annular flange at the bottom which is clamped to the base by a ring 14. The top 12 and bottom 11 have ball bearings 15, 16, the latter being in a screw plug 17, said plug being received in a depending threaded boss 18 on the bottom 11. A vertical shaft 19 turns in the bearings 15, 16 and on said shaft is a flywheel 20 constituting 70 a power wheel. A drive wheel 21 turns on a vertical shaft 22 carried on a swingable spring pressed frame 22^a pivoted as at 22^b and acted on by any suitable spring 22^c, whereby the frame and drive wheel may be 75 80 swung into or out of driving connection with the shaft 19. The said drive wheel 21 projects laterally through an opening in a side of the base 10 between brackets 23 housing the major portion of the projecting part of 85 the wheel leaving the periphery of said wheel exposed. By the operator grasping, or frictionally engaging the wheel 21 by a tangential movement of the hand, sufficient momentum is given to the shaft 19 with its 90 power wheel 21 to store up the power necessary to give a sustained driving movement to the sharpener. To prevent reverse movement of wheel 21, a brake dog 21^a pivoted at 21^b is adapted to engage said wheel; 21^c is a 95 resistance stud beneath the wheel.

The upper end of the shaft 19 extends above the top 12 and has secured thereto the cutter head 24, the body of which generally is in the form of a shell, said cutter 100 head being secured to the shaft in any suitable manner as by means of a threaded tenon 26 on the shaft to be received in a threaded socket in the under side of the bottom 25 of the cutter head. Knives 27 as 105 shown best in Fig. 6 are provided in the cutter head 24, the said knives at the lower end being mounted and resting in grooves

28 in the upper side of the bottom 25. At the opposite end each knife 27 is formed with a laterally offset pin 33 arranged for radial adjustment by the means next described. In the top of the cutter head 24 are upper and lower concavo-convex disks 29, 30. The lower disk 30 is formed with radial slots 31 and the upper disk 29 has eccentric slots 32 through which slots the 10 pins 33 of the knives project, the upper ends of the pins being received in a clearance space or groove 34^a in a cap nut 34 which is received on a threaded boss 30^a on the disk 30, said boss extending through the 15 center of the upper disk 29.

The cutter head 24 is provided also with conical guide rollers 35 turning in carriers 36, one bearing 37 of each roller 35 being in the form preferably of a screw pin passing 20 through the upper end of the carrier 36 and extending through a boss 38 thereon, said boss being disposed in a radial slot 39 of the lower disk 30 and the projecting end of the pin 37 extending through an eccentric slot 40 in the upper disk 29, said pins projecting into the clearance space or groove 34^a of the cap nut 34. The disk 29 is formed with knobs 29^a whereby it may be turned, and it will be obvious that the turning of 25 the disk 29 will cause the eccentric slots 32 and 40 to move the pins 33 of the knives 27 and the pins 37 of the roller carriers 36 radially in the respective slots 31, 39, whereby to adjust the angular positions of the knives 30 and rollers relatively to the axis of rotation 35 of the cutter head.

The sides of the shell 24 are formed with openings 41 for the escape of the shavings of the pencil and these may be removed 40 through a side opening 42 in the dome 13.

The pencil A is passed through the top of the dome 13 which has an opening aligning with the axis of the cutter head. Preferably in the opening is a cap 43 which may 45 be secured by a ring 44 threaded on the neck at the interior of the dome. The neck 43 may receive a bushing 45 adapted to slide and turn therein. Said bushing is turned exteriorly with a slight taper at its upper 50 end 46 and said upper end is slotted longitudinally at a desired number of points as at 47 whereby a sliding clamp ring 48 will serve to tightly bind the bushing on the pencil A. The surface of one or both rollers 55 35 preferably is ribbed or formed with parallel angular grooves, whereby the turning of the rollers tends to feed the pencil to the cutters. The sleeve 49 is particularly useful in forming a long taper on the pencil with- 60 out danger of breaking the point.

In the form shown in Fig. 10, the knives and guide rollers are fixed. In this form the shell 24^a corresponding with the shell 24 is suitably secured to the shaft 19^a and 65 the knives 27^a are formed with flanges 27^b

at the upper and lower ends, the flanges being secured by screws 27^c or the like to the top 24^b and bottom 24^c of the shell. The rollers 35^a are secured in fixed position in the top 24^b by screws 49 or equivalent means. 70

We wish to state in conclusion that although the illustrated example constitutes a practical embodiment of our invention, we do not wish to limit ourselves to the mechanical details herein illustrated, since 75 manifestly the same can be considerably varied without departure from the spirit of the invention as defined in the appended claims.

Having thus described our invention, we 80 claim as new, and desire to secure by Letters Patent:

1. A cutter head for pencil sharpeners, including cutters supported in said head, conical rollers in said head between the cutters, 85 said cutters and rollers being adapted to accommodate a pencil therebetween and being inclined to the axis of rotation of the cutter head, and a tubular pencil holding device revolvably and slidably supported 90 above the cutter head and coaxial with the latter.

2. A cutter head for pencil sharpeners, including knives, and feed and guide rollers rockably supported at one end in the head 95 and radially adjustable at their opposite ends in said head.

3. A cutter head for pencil sharpeners, including cutters supported in said head, and conical rollers in said head between the 100 cutters, said cutters and rollers being adapted to accommodate a pencil therebetween and being inclined to the axis of rotation of the cutter head, one of said rollers having ribs thereon.

4. A cutter head for pencil sharpeners adapted to receive a pencil axially therein, a knife positioned in said head to act on the inserted pencil, and a conical roller on said head in position to engage the inserted 110 pencil, said roller being roughened to have a feeding action on the pencil.

5. A cutter head for pencil sharpeners, including cutters supported in said head, and conical rollers in said head between the 115 cutters, said cutters and rollers being adapted to accommodate a pencil therebetween and being inclined to the axis of rotation of the cutter head; together with means to vary the angular positions of the said 120 cutters and rollers.

6. In a cutter head for pencil sharpeners, the combination of knives rockably supported at one end in the cutter head, concavo-convex disks on the cutter head at the 125 opposite end, one of said disks being turnable and formed with eccentric slots, and the other of said disks having radial slots, guide rollers between the knives, the knives and rollers being disposed at an angle to 130

the axis of rotation of the cutter head, carriers for said rollers, the said knives and carriers each having a member projecting through a radial and conical slot in the respective disks, and means to turn the disk having the eccentric slots to vary the angular positions of the knives and rollers.

7. A cutter head for a pencil sharpener, including a knife rockably supported at

one end in the cutter head and formed with 10 an offset pin at the opposite end, and means to radially move said pin to adjust the angular position of the knife in the cutter head, said means including a revoluble disk having an eccentric slot in which the pin of 15 the knife is received.

THOMAS ALFRED RUDDLE.
NIELS CHRISTIAN AHL.
